UNITED STATES PATENT OFFICE.

HENRY SIMS, OF ERIE, PENNSYLVANIA.

LOW-WATER ALARM.

SPECIFICATION forming part of Letters Patent No. 417,517, dated December 17, 1889.

Application filed February 16, 1889. Serial No. 300,199. (No model.)

To all whom it may concern:

Be it known that I, HENRY SIMS, a citizen of the United States, residing at Erie, in the county of Erie and State of Pennsylvania, have invented certain new and useful Improvements in Low-Water Alarms; and I do hereby declare the following to be a full, clear, and exact description of the invention, such as will enable others skilled in the art to which it appertains to make and use the same, reference being had to the accompanying drawing, and to the letters of reference marked thereon, forming part of this specification.

My invention consists in the improvements in low-water alarms for steam-boilers, herein-after set forth, and explained and illustrated in the accompanying drawing, in which—

The figure shows a cross-section of a steam-boiler with my improved low-water alarm in place thereon, a portion of the device being shown in section.

The objects of my invention are to construct a low-water alarm for steam-boilers with a dry-steam passage to the alarm-whistle and to so simplify the mechanism of the device as to do away with the lost motion incident to the compound-lever mechanism ordinarily provided for operating the alarm-whistle, and also adapt the whistle to be operated either by the operation of the expansion mechanism or by moving the whistle-valve lever by hand.

In the construction of my device shown, A is the shell of a steam-boiler, and α the low-water line thereof. In the top of the boiler-shell A, preferably near the front end thereof, I secure the shell B by means of the screw-thread b, which fits into the screw-threaded opening in the boiler. The upper end of this shell B is provided with a sleeve-extension C, which is internally screw-threaded from end to end. In the lower portion of the sleeve C, I secure a short section of pipe D, which extends down through the shell B into the boiler to the low-water line α , and in the upper portion of the sleeve C, I secure an expansion-pipe E, which extends upward some distance and is provided with a cap F, its upper end having an ear f on one side thereof.

In the side of the shell B and communicating with the chamber therein is secured an

elbow G, which opens upward, into which elbow a nipple H is screwed, which nipple communicates with and supports a steam-whistle I, the valve mechanism of which is of usual and ordinary construction.

In the whistle-valve lever J, a short distance outside of the pintle h, upon which the lever J oscillates, I make a vertical slot j, and in this slot j, I insert the hook l on the lower end of a rod L, which extends therefrom upward and through an opening in the ear f in the cap F, the upper end of the rod L being screw-threaded and provided with adjusting-nuts g g', by means whereof the length of the rod L between the ear f and the slot j in the whistle-valve lever J can be so adjusted as to take up all lost motion and cause a slight expansion of the pipe E to raise the lever J and open the whistle-valve. The object of inserting the hook l on the lower end of the rod L in a slot j in the whistle-valve lever J is to permit the raising of the lever J by hand, the hook l on the lower end of the rod L passing downward in the slot j during this operation, thus adapting the whistle to be operated either by the expansion mechanism as a low-water alarm, or by hand for ordinary purposes for which whistles in shops are used.

In operating as a low-water alarm, when the water in the boiler is above the line α and the lower end of the pipe D, the pipe D and the expansion-pipe E are filled with comparatively cold water; but as soon as the water in the boiler falls below the lower end of the pipe D the water in the pipes D and E drains into the boiler and hot steam takes its place, which rapidly heats the expansion-pipe E, which operates by means of the connecting-rod L to raise the whistle-valve lever J and open the whistle-valve, when dry steam passes from the upper portion of the boiler and the chamber in the shell B to the whistle, thereby operating it to sound an alarm, which alarm continues to sound until the water in the boiler is raised above the lower end of the pipe D, when the steam in the expansion-pipe E soon condenses and its place is filled with water, which soon cools, causing the pipe E to contract, thereby releasing the valve-lever J, which then operates by its weight to close the whistle-valve, this alarm operat-

ing automatically, as described, whenever the water in the boiler falls below the lower end of the pipe D.

I am aware of the patents of Bradford, No. 5 113,843, dated April 18, 1877. Therefore I do not claim, broadly, the feature of separate passages from the boiler to the expansion-pipe and to the alarm-whistle, as a device of this character is shown in that patent; but 10 What I do claim as new, and desire to secure by Letters Patent of the United States, is—

1. The combination, in a low-water alarm, of a whistle I, having a downwardly-projecting valve-lever J, provided with a slot *j*, with the expansion-pipe E and adjustable rod L, extending from the slot *j* in the whistle-valve lever J to the ear *f* on the expansion-pipe cap 15

F, substantially as and for the purpose set forth. 20

2. The combination, in a low-water alarm, of the shell B, having the downwardly-projecting pipe D and the upwardly-extending extension-pipe E, secured therein, and having an elbow G on the side thereof supporting a 25 whistle I, with the adjustable rod L, extending from the ear *f* on the cap F to and into the slot *j* in the whistle-valve lever J, substantially as and for the purpose set forth.

In testimony whereof I affix my signature 30 in presence of two witnesses.

HENRY SIMS.
